UNITED STATES PATENT OFFICE.

ALFRED M. SIGNALNESS, OF NORTH BEND, OREGON.

SAWING MACHINE.

Application filed October 28, 1922. Serial No. 597,599.

To all whom it may concern:

Be it known that I, ALFRED M. SIGNALNESS, a citizen of the United States, and a resident of North Bend, in the county of Coos and State of Oregon, have invented certain new and useful Improvements in Sawing Machines, of which the following is a specification.

This invention relates in general to a sawing machine and more particularly adapted for a sawing machine in conjunction with a pile driving rig for cutting off the tops of piling to enable the placing of the caps thereon.

The object of the invention is to provide a sawing machine of this character which speedily and quickly cuts off tops of the piling and which is not only under the complete and positive control of the operator but which is also adjustable so as to make allowance for grade or the like that may be required in practice.

Other objects and advantages of the invention reside in certain novel features of the construction, combination and arrangement of parts which will be hereinafter more fully described and particularly pointed out in the appended claims, reference being had to the accompanying drawings forming part of this specification and in which:

Figure 1 is a perspective view, showing the sawing machine organized with a pile driving rig;

Figure 2 is a fragmentary perspective view, illustrating the hanger and associated parts;

Figure 3 is a similar view of the power operated saw and associated parts;

Figure 4 is a view in transverse vertical section through the hanger and saw cylinder, parts being shown in elevation for the sake of illustration;

Figure 5 is a view in transverse section, taken approximately on line 5-5 of Figure 3;

Figure 6 is a group view in perspective, showing in detail the bearing plate and associated collar and locking pin;

Figure 7 is a detail view in perspective, illustrating the actuated key; and

Figure 8 is a detail view in elevation, showing the anchoring dog or rod.

Referring to the drawings wherein for the sake of illustration is shown the preferred embodiment of the invention, the numeral 10 designates a pile driving rig which may be of any conventional construction and which along with the other instrumentalities usually employed comprises runners 11 upon which the boiler or other source of steam supply 12 is supported.

Adjacent the outer end of the runner 11 a horizontally disposed supporting shaft 13 is arranged and is supported in fixed position on the runner by means of brackets 14.

A hanger, designated generally at 15 is mounted on the supporting shaft by means of spaced bearing sleeves 16 formed at the upper end of the hanger and embracing the shaft 13, these sleeves 16 having a working fit on the shaft so that the hanger which normally depends from the shaft 13 may be adjusted longitudinally on the shaft and also rotated or adjusted angularly about said shaft. A power operated saw, designated at 20, is mounted on the hanger and includes a steam cylinder 21 supplied with steam from the boiler 12 by means of a pipe 22, the flow of steam into the steam cylinder being regulated by any conventional or desired valve means. The saw blade 23 is driven by a piston rod 24 from a piston which is operatively mounted in the steam cylinder and this saw 23 is braced and guided in its reciprocal movements by means of a combined brace and guide 25 carried by the cylinder and comprising a yoke, the arms of which are provided with guide slots 26. The arm of the yoke 25 which is connected to the cylinder is of U-shaped form, as indicated at 27, and includes a bearing 28 for the piston rod as well as the guide grooves 26.

The steam cylinder 21 has integrally formed therewith or suitably connected thereto a bearing block 30 having an opening 31 extending therethrough and a keyway 32 formed therein and communicating with the opening.

On the hanger 15 a pair of spaced ver-

tically alined and apertured bearing lugs 35 are formed and rotatably receive a vertical shaft 36. In the assembly this shaft 36 extends through the opening 31 of the block 30 and a key 37 which is associated with the shaft 36 and fitted in the key-way 32 constrains the block and consequently the saw to partake of the rotary movement of the shaft 36 while permitting the longitudinal adjustment of this bearing block and saw on the shaft. In order that the degree of vertical adjustment of the steam cylinder on the shaft 36 may be precisely determined, one of the exposed faces of the key 37 is provided with graduations 38, as clearly shown in Figure 7. These graduations indicate in inches or in any desired system of units the degree of vertical adjustment.

Means is provided for effecting vertical adjustment of the saw cylinder on the shaft 36 and preferably comprises a screw shaft 40 having threaded engagement with an internally threaded opening 41 formed in the bearing block 30 and itself supported on a bearing plate 42 fitted on the shaft 36 above the lug 35 and secured to this shaft by a set screw or the like as indicated at 43, a collar 44 being fixed to the screw shaft 40 and engaging the plate 42 to prevent downward displacement of the screw shaft. By mounting the screw shaft in this manner it is capable of readily effecting vertical adjustment of the steam cylinder without interfering with horizontal swinging movement thereof.

The upper ends of the shafts 36 and 40 are squared, as indicated at 45 and 46, respectively, and these squared ends of the shafts are selectively co-operable with the squared socket 47 of the operating handle 48. When the socket 47 is engaged with the squared end 46 of the screw shaft 40 this screw shaft may be turned to effect vertical adjustment of the steam cylinder on the shaft 36. On the other hand when this squared socket is engaged with the end 45 of the shaft 36 the handle may be utilized to control the horizontal swing as well as the longitudinal adjustment of the power operated saw. The vertical adjustment which may be effected in the manner hereinabove described is especially advantageous when it is necessary to cut off the piling on the grade since the desired rise or fall may be given by cutting off more or less at each set of piling, this being regulated by the vertical adjustment of the saw effected by the screw shaft.

At times it is desired to swing the hanger up onto the deck or top of the runners. The hanger and the power operated saw are capable of partaking of this movement and they may be readily actuated through such movement by a conventional block and fall or by means of a small tackle. When undergoing such movement, however, it is neces-

sary that the power operated saw be held from horizontal swinging movement and in order to carry out this purpose the bearing plate 42 is provided with an opening 42a adapted to be brought into register with a similar opening in the bearing lug 35. A locking pin 50 may then be inserted through the registering opening and will serve to hold the power operated saw against horizontal swinging movement.

An anchor rod or dog 55 is associated with the saw cylinder by means of a clamp 56 and may be engaged with the pile during the sawing action.

I claim:

1. In a sawing machine, a horizontally disposed supporting shaft, a hanger mounted on said shaft for longitudinal and angular adjustment, a power operated saw including a cylinder having a bearing block formed thereon, a rotatable vertical shaft mounted on the hanger, said bearing block being fitted on said shaft so as to be constrained to partake of the rotary movement of the shaft while free to be vertically adjusted thereon, a screw shaft cooperable with the bearing block for effecting vertical adjustment of the cylinder, and a handle selectively cooperable with the screw shaft or vertical shaft.

2. In a sawing machine, a horizontally disposed supporting shaft, a hanger mounted on said shaft for longitudinal and angular adjustment, a power operated saw including a cylinder having a bearing block formed thereon, a rotatable vertical shaft mounted on the hanger, said bearing block being fitted on said shaft so as to be constrained to partake of the rotary movement of the shaft while free to be vertically adjusted thereon, and a screw shaft cooperable with the bearing block for effecting vertical adjustment of the cylinder.

3. In a sawing machine, a hanger, a power operated saw having a bearing block, a rotatable vertical shaft carried by the hanger, said bearing block being fitted on said vertical shaft, a key cooperable with the bearing block and with the vertical shaft for constraining the bearing block to partake of the motion of the vertical shaft while permitting longitudinal adjustment of the block on the shaft, said key having an exposed face provided with graduations indicating the degree of vertical adjustment, and means for vertically adjusting the block on the shaft.

4. A sawing machine for use with a pile driving rig for cutting off the tops of piling and comprising a horizontal supporting shaft, means for securing said shaft to a runner of the pile driving rig, a hanger slidably and rotatably mounted on said shaft, a power operated saw, and means for mounting said saw on said hanger for vertical ad-

justment and for horizontal swinging movement.

5. In a sawing machine, a supporting shaft, a hanger mounted on said supporting shaft for longitudinal adjustment and swinging movement in a vertical plane, a power operated saw mounted on the hanger

for vertical adjustment and for swinging movement in a horizontal plane, and locking mechanism for holding the saw against horizontal swinging movement relative to its hanger while permitting the hanger to partake of vertical swinging movement. 10

ALFRED M. SIGNALNESS.
